UNITED STATES PATENT OFFICE

AARON ROSENSTEIN, OF NEW YORK, N. Y., ASSIGNOR TO ROSENSTEIN BROS. & HOOK, OF NEW YORK, N. Y., A CORPORATION OF NEW JERSEY

ADVERTISING SIGN

Application filed February 2, 1929. Serial No. 337,004.

My present invention relates to advertising signs, and more particularly to an advertising sign for use on aeroplanes.

Advertising signs for use on the wings of aeroplanes, as heretofore constructed, have been impractical for a number of reasons. One of the objections is due to the fact that the signs have not been completely interchangeable. Another objection has been 10 that the signs have not conformed to the lines of the aeroplane wing, thus interfering with the speed of the aeroplane.

My invention is an improvement on the advertising sign patents of Mitchell and La 15 Grassa, No. 1,474,682, La Grassa, Nos. 1,505,714 and 1,509,046, and Hook, No. 1,506,638.

The principal object of my invention is to 20 provide an advertising sign for use upon aeroplanes or the like in which the sign letters or panels will be completely interchangeable.

Another object of the invention is to provide a sign which will substantially conform 25 to the lines of the wings of the aeroplane, so that the surface of the sign will be flush with the surface of the wing.

A still further object of the invention is to 30 provide a sign of this type which can be readily attached to the aeroplane.

Other objects and advantages will be apparent from the following specification and drawing, in which

Figure 1 is a view of the under surface of a 35 portion of the lower wing of a metal aeroplane,

Figure 2 is a section on the line 2—2 of Fig. 1,

Figure 3 is a section on the line 3—3 of Fig. 2,

Figure 4 is a longitudinal cross section of a fabric-covered aeroplane wing, showing the method of attaching my sign thereto,

45 Figure 5 is a view of a luminous vapor tube

formed into a letter and particularly adapted for use with aeroplanes,

Figure 6 is a top edge view of the letter shown in Fig. 5,

Figure 7 is a view of the lower surface of a 50 portion of the lower wing of a metal aeroplane, showing a modified form of sign structure.

Figure 8 is a cross-sectional view taken on the line 9—9 of Fig. 7, and

Figure 9 is a sectional view, similar to Fig. 8, showing the method of attaching the sign panel shown in Figs. 7 and 8 to a fabric-covered aeroplane wing.

In the form of the invention shown in Figs. 60 1 to 3, the numeral 10 designates the lower wing of an aeroplane the fuselage of which is indicated by the numeral 80. Luminous vapor tubes 23 formed to the outlines of letters are shown attached to the lower surface of the wing 10 by means of clamps or brackets 14. The clamps or brackets 14 are generally U-shaped so as to conform to the outline of the tubes 11, and are provided with ears 35 adapted to bear against the 65 under surface of the aeroplane wing. The clamps or brackets 14 are held upon the lower surface of the wing 10 by means of bolts 28 extending through the ears 35 and threaded into nuts 29 carried in slotted ways 12, 70 75 As shown in Fig. 1, groups of slotted ways 12, 13, and 15 are provided on the lower surface of the wing 10, each group being adapted to hold a single letter tube 11. In order that new letter tubes may be affixed to each group of slots or letter position, it is preferable to provide several longitudinally extending slots 12, an upper central slot 13, an upper corner slot 13', a lower central slot 15, and a lower corner slot 15'.

As has been stated above, in order to hold sign letters upon the wings, the bolts 28 extend into the slots 12, 13, 13', and 15', in accordance with the outline of the letters to be secured, and engage the nuts 29. The nuts 80 85 90

29 are held in alignment with the slotted ways 12, 13, 13', and 15' by means of the plates 16 which are secured to the inner surface of the under side of the wing by means of set screws 18. The plates 16 are provided with a central groove 17 in alignment with the slots 12, 13, 13', 15 and 15', the groove 17 being so shaped as to prevent rotation of the nuts 29. A number of nuts sufficient for all purposes may be placed in the groove 17 of the plate 16 when the plane is constructed, or at any time thereafter. When a letter tube 23 is to be attached to the wing, it is merely necessary to slide the nuts 29 to points where they will be in alignment with the positions which must be given the bolts 28 and clamp 14 to secure the desired letter to the wing. The bolts 28 will then be tightened to draw the clamp 14 securely against the letter tube 11.

It is believed that the showing in the drawing of the arrangement of the clamps 14 for attaching the letters "A", "E", "R", "O" upon a plane will clearly indicate the various positionings of the clamps which must be worked out to secure various letters of the alphabet.

In order to supply current to the luminous letter tubes 23, a group of contact sockets 27 is provided with each group of letter-positioning slots 12, 13, 13', 15 and 15'. By providing a plurality of sockets 27, it will be possible to supply current to a tube formed into any letter. The tube contact plugs 92 are flexibly secured to the tube by means of wires 91 of opposite polarities leading into the rear face of the tubes at two points as is customary in sign letters of this type. Electric current may be supplied to the sockets 27 from a generator or any suitable source upon the aeroplane.

In Fig. 4, I have illustrated a fabric-covered aeroplane wing 19 to which luminous letter tubes may be attached in much the same manner as has been described above. Brackets 14 will be secured to the aeroplane wing by means of screws 34 extending into the spars 20 of the wing. In the event that the spars 20 are not sufficiently close together to accommodate the desired number of letter tubes, additional spars or cross members 22 may be built into the wing 19.

In Figs. 5 and 6, I have illustrated a form of luminous sign letter tube which is particularly adapted for use on aeroplanes. For the purposes of showing my invention, I have illustrated it as applied to the letter "A". However, it will be understood that it may be used in the construction of any luminous letter tube. In forming the tube, the upper edge of the upper portion 24 of the letter is tapered down on its upper or exposed side. The under surface of the letter tube (the surface which contacts with the aeroplane wing) is made substantially flat. This arrangement results in the provision of a knife edge on the

portion of the letter facing in the direction of flight of the aeroplane and thus cuts down wind resistance. The trailing edge of the letter tube 26 may also be streamlined, as shown. In forming the letter "A" it will of course be understood that the entire outer and upper edge 25 of the letter should preferably be streamlined, thus avoiding the wind resistance which might occur if the sides of the letter were formed in the usual manner.

In Figs. 7 and 8, I have illustrated an arrangement for attaching sign panels or letter panels to the under surface of the lower wing of an aeroplane in such a manner that the surfaces of the panels will be flush with the surface of the aeroplane wing. The numeral 40 designates the lower wing of a metal aeroplane. Letter panels 41 are secured to the under surface of the wing 40 by means of set screws 43. As shown in Fig. 8, the side edges of the panels 41 are angled or off-set, as indicated by the numeral 49, so that they may be fitted into slide ways 44 extending from the front to the rear edges of the aeroplane wing 40. The set screws 43 extend through the off-set portions 49 of the letter panels, so that the latter are securely held in position.

The panels 41 are preferably formed of metal sufficiently flexible to conform to the curving outline of the aeroplane wing, and the letters 47 outlined in the panels 41 are preferably formed of celluloid, so that they will be flexible as well as translucent, although the letters may be formed of sections of glass so arranged as to give the desired flexibility. The celluloid or glass or the like may be held in place in the panels 41 by means of clamping plates 60 secured to the lower surface of the panels by screws 61. Light bulbs 46 are mounted in reflectors 45 beneath the panels 41 so as to illuminate the letters 47. Electric current to illuminate the bulbs 46 may be supplied from a generator or the like carried on the aeroplane.

In Fig. 9, I have shown an arrangement for securing letter panels to fabric-covered aeroplane wings. It will be seen that the panels 41 are secured in exactly the same manner as is described above in connection with Figs. 7 and 8, except that the edges 49 of the panels are mounted in spars or additional cross pieces 48. The light bulbs 46 are mounted upon supports 50 extending between the spars or cross pieces. Reflectors may be provided if desired.

I claim:

1. The combination with an aeroplane wing, said wing having a plurality of slots in the surface thereof and arranged in an angularly disposed group, of a luminous letter tube, removable securing elements adapted to secure said tube against the surface of the wing, said elements being selectively positioned in the slots of said wing, and an electric socket for supplying current to said tube.

2. The combination with an aeroplane wing having a plurality of slots in the surface thereof and arranged in angularly disposed groups, of an outline sign letter adapted to be placed against the surface of the wing and means adapted to secure the letter to the wing comprising brackets selectively positioned in the slots in the wing surface.

3. The combination with an aeroplane wing, said wing having a plurality of angularly arranged slots therein, of a letter and movable elements adapted to secure said letter to the wing, said elements being selectively positioned in the slots in said wing.

15 AARON ROSENSTEIN.
